(57) **CLAIM**

The ornamental design for the projection mount, as shown and described.

DESCRIPTION

FIG. 1 is a front perspective view of the projection mount;
FIG. 2 is a front view thereof;
FIG. 3 is a right side view thereof;
FIG. 4 is a top plan view thereof;
FIG. 5 is a bottom plan view thereof;
FIG. 6 is a rear view thereof; and,
FIG. 7 is a left side view thereof.

The broken line shown in FIG. 5 is included for the purpose of illustrating portions of the projection mount that form no part of the claimed design.
